UNITED STATES PATENT OFFICE.

NICHOLAS P. LEHR AND JOSEPH W. LEHR, OF FREMONT, OHIO.

DESIGN FOR A STANDARD FOR CULTIVATOR-TEETH.

SPECIFICATION forming part of Design No. 15,148, dated July 15, 1884.

Application filed March 27, 1884. Term of patent 7 years.

To all whom it may concern:

Be it known that we, N. P. LEHR and J. W. LEHR, citizens of the United States of America, residing at Fremont, in the county 5 of Sandusky and State of Ohio, have invented and produced a new and original Design for Standards for Cultivator-Teeth, of which the following is a specification, reference being had therein to the accompanying drawing.

10 Our design pertains to a cultivator-standard, the front portion of the standard being inwardly curved at about the center of its length, its rear comprising an outwardly - curved brace, its center being a reticulated web, C, 15 the upper face thereof being flattened, save where interpose apertures F and rib or stud E.

In the accompanying drawing, which is illustrative of a perspective view of a cultivator-standard embodying our design, A is 20 the front portion of the standard, which has an inward curvature or concavity, a, at about its center. Its brace B (represented at the rear) has an outward curvature or convexity, while 25 intermediately the standard and brace are connected by a reticulated web, C, which renders the cultivator - standard attractive and

symmetrical. Through the extreme lower part of the standard, and extending rearward through the web and brace in tubular form, is an aperture, D, while on the upper face, G, 30 is an aperture, F, and a rib or stud, E, integral with the standard.

Having thus fully described our design, what we claim, and desire to secure by Letters Patent, is—

The design for a cultivator-standard, the same consisting of the body having its front portion inwardly curved at about the middle of its length, as at a, its rear portion having an outward convexity, as at B, the reticulated 40 web C, the cylinder D, extending through and integral with the web and brace, and the upper face, G, having a square vertical aperture, F, and nib or stud E integral therewith, as shown.

In testimony whereof we affix our signatures in presence of two witnesses.

NICHOLAS P. LEHR.
JOSEPH W. LEHR.
